Patented Dec. 17, 1912.

UNITED STATES PATENT OFFICE.

ALBERT M. E. GRIGNARD, OF NEW YORK, N. Y.

MEANS FOR SUPPORTING CYLINDERS.

1,047,206.

Specification of Letters Patent. Patented Dec. 17, 1912.

Application filed April 1, 1912. Serial No. 687,942.

To all whom it may concern:

Be it known that I, ALBERT M. E. GRIGNARD, a citizen of the United States, residing at New York city, in the county of New York and State of New York, have invented certain new and useful Improvements in Means for Supporting Cylinders, of which the following is a specification, reference being had therein to the accompanying drawings.

My invention relates to improvements in supports for cylinder, rollers or printing cylinders and has particular reference to and is illustrated in the accompanying drawings in its application to a printing roller.

Figure 1 is a front elevation of a printing cylinder in dotted outline showing at the left the supporting means adapted to reinforce and retain the cylinder in position. Fig. 2 is an enlarged longitudinal elevation partly broken away illustrating the arrangement of the combination when in position for use. Fig. 3 is a cross section on the line 3—3 of Fig. 2 looking from right to left, and Fig. 4 is an enlarged longitudinal section of the left hand portion of Fig. 2 showing the method of tightening up the support for the cylinder.

5 is a shaft mounted upon the standards, 30 6, 7 and 8, the standard 6 being provided with the usual bearing 9 which may be permanently bolted down in position. The bearings of the standards 7 and 8 are preferably provided with caps 10 and 11 which 35 may be opened by loosening the nuts 12 and 13 after which the caps may be thrown open upon the pins 14 and 15. The standards 7 and 8 are also adapted to slide back and forth upon the bases 16 and 17 into which 40 they are keyed as shown.

18 is the printing cylinder suitably engraved or otherwise prepared and 19, 20 and 21 are the three longitudinal sections of the expansible support or reinforcements 45 adapted to conform to and engage the interior of the cylinder. These longitudinal sections are also preferably provided with keys 22, 23 and 24 which engage the inner expanding element or core 25 which is tapered as shown and is keyed fast upon the shaft 5 by a key such as 26.

At one extremity of the shaft 5 is preferably rotatably mounted a worm wheel provided with a shank or sleeve which may be 50 fastened thereto after adjustment by any

suitable means such as the screw 28. This sleeve is preferably held close up against the extremity of the core 25 by the collar 29 which is also locked to the shaft by a suitable screw such as 30. The shank or 60 sleeve 27 of the worm wheel is also preferably provided with suitable means for turning the same such as the nut 31 or holes 32 through which a suitable pin may be introduced. The threads 33 of the worm are 65 adapted to engage the teeth 34 of the racks upon the interior of the longitudinal sections 19, 20 and 21. These teeth may be cut into the keys 22, 23 and 24 of said sections. From this it will be seen that when the 70 parts are assembled as shown the nut 31 may be turned thus causing the sections 19, 20 and 21 to draw up upon the tapered core. The tapered construction of the sections 19, 20 and 21 and the tapered construction of 75 the core 25 cause the sections 19 to 21 inclusive to radiate outwardly against the interior of the cylinder 18 when the sections are drawn upon the tapered core as stated, thus securely and uniformly binding and 80 reinforcing the said cylinder throughout its entire length.

85 35 to 38 inclusive are suitable webs, ridges or partitions which may be distributed at various points according to the pressure to which the cylinder is to be subjected.

39 is a driving pulley illustrating a method by which the cylinder is rotated.

To place the cylinder upon the sections 19 to 21 inclusive, the standard 8 is slipped 90 backward upon the base 17 after the cap 11 has been opened or removed. The cylinder 18 is then lifted over the shaft 5 and placed at rest upon the blocks 40—40'. The standard 8 is then returned to its original 95 position and the cap secured by the nut again as before. The standard 7 is now slid back upon its bearing 16 after the cap 10 has been opened or removed and the cylinder 18 is then slid over the sections 19 to 100 21 inclusive after which the sections may be expanded by turning the worm wheel as before stated. To remove or replace the cylinder 18 it is only necessary to turn the worm wheel in the opposite direction by the nut 105 31 when the sections will contract. By then sliding the bearing 7 out of the way, it will be an easy matter to draw off the cylinder 18 after which the central standard 110 and bearing may be replaced. The stand-

55 115

ard and bearing at the right hand end may then be slid back and the cylinder may be readily removed.

Of course it will be readily understood that various modifications may be made without departing from the spirit of the invention as set forth in the claims.

I claim:

1. A contractible and expandible support for a printing form comprising a plurality of radially adjustable supporting sections, a tapered core, means for moving said sections longitudinally, keyways in said core and keys of said sections engaging said keyways, said means comprising teeth cut in said keys, a worm wheel mounted concentric with said core adapted to engage said teeth and adapted to move said sections when said worm wheel is rotated.
- 10
- 15

2. A contractible and expandible support for a cylinder comprising a plurality of radially adjustable supporting sections, a tapered core and means for moving said sections longitudinally, keyways in said core and keys of said sections engaging said keyways, said means comprising teeth in said keys and a worm wheel adapted to engage the same and adapted to move said sections upon said core when said worm wheel is rotated, said worm wheel having a sleeve or shank provided with means for rotating the same.

In testimony whereof I affix my signature in presence of two witnesses.

ALBERT M. E. GRIGNARD.
